DEVICE FOR DRESSING SCREW-THREAD-
GRINDING DISKS

Hans Brendel and Erich Buchholz, Hamburg-Wandsbek, Germany, assignors to Bauer & Schaurte, Neuss-on-the-Rhine, Germany, a corporation of Germany

Application April 2, 1938, Serial No. 199,666
In Germany April 3, 1937

4 Claims. (Cl. 125—11)

This invention relates to a device for dressing disks for grinding screw-threads.

Heretofore, in the grinding of screw-threads, it has been practically impossible to obtain microscopic trueness in the grinding disk. This was fundamentally true because in trimming the grinding disk with grinding tools, primarily diamond cutters, the trimming was done by putting the cutters against the grinding disk and cutting one side first, and then cutting the opposing side. In this manner, the grinding disk resulting was untrue and consequently unfit for precision work.

Other means have been suggested, but none have been successful, since the pressures of the grinding and profile-finishing tools were unequal on opposing sides of the grinding disk per se.

The present invention contemplates utilizing an apparatus wherein the diamond-trimming and profile-finishing tools afford equal and opposite pressures on the respective grinding surfaces of the disk to be dressed.

It is an object of this invention to provide grinding disk trimming means wherein the pressures of the disk trimmers per se will be equal and opposite against the grinding disk.

A further object is to provide a device for dressing grinding disks per se by causing a series of tools to engage opposite sides of the grinding surfaces of a grinding disk while utilizing equal tool pressures simultaneously on opposite sides of the working flanks of a grinding disk.

Further and other objects may become apparent to those skilled in the art from a perusal of the drawing and specification herewith.

In the drawing:

Fig. 1 shows diagrammatically a dressing device for a screw-thread-grinding disk;

Fig. 2 shows substantially the same parts as in Fig. 1, but the arrangement thereof is different to present special working conditions; and

Fig. 3 shows in section a device for effecting the external roundings of the grinding disk for the production of round thread profiles.

Similar characters of reference indicate corresponding parts throughout the various views.

Referring more particularly to Fig. 1, the dressing of the flanks of a profile grinding disk by means of simultaneous longitudinally moving tools is carried out. The diamond carriers *d* provided with the diamonds *d'* are adapted to be reciprocated in their holders in the direction of the arrows *11*.

55 In the embodiment illustrated, the flanks *a*

and *b* of the disks are shouldered, providing the transition stages *c*. It will be seen from Fig. 2 that the disk *10* is engaged on one side by diamonds *d'* carried by the tool carrier *12*. The diamonds *d'* of the tool carrier *13* are moved out of engagement with the disk *10*. The resultant pressure therefore causes the displacement angle *h* between the true center shown as dash-dot line *14*, and the resultant center shown by dash-dot line *15* caused by the pressure of the tools of the tool carrier *12*.

It will therefore be seen that to produce the trimming of the wheel *10* by the cutters *d'* of tool carrier *12*, the pressure of necessity must be such that it is impossible to avoid the disk from moving from the line *14* to substantially a line approximating line *15*.

In Fig. 1 it is seen that the tool carriers *d* have the individual components *12* and *13*, which components may move to and fro along the flanks *a* and *b* of the grinding disk, and said to and fro movement may be either in the same general direction at one time, or they may be moving in opposite directions at substantially the same time. Whether or not the tool carriers *12* and *13* move in the same general direction, or whether one moves in one direction while the other moves in an opposite direction, is entirely dependent upon the pressures presented by the diamonds to the surfaces *a* and *b* of the grinding disk. The displacement caused by the movement of the tool carriers *12* and *13* in the directions of the arrows *11* is generally quite small as long as the diamond cutters on opposite sides of the disk are engaging the disk simultaneously, there will be substantially an absolute elimination of the angle *h*.

Fig. 3 shows how the end faces *c* are used for the production or dressing of the concave rounding or curved working face *e* on Whitworth 40 and other round thread profiles. There is also shown the mode of operation of a disc or roller *f* of steel, hard metal or the like, which produces the convex rounding surfaces *e* simultaneously with the rounding of the core-forming portion 45 or apex *g* on the grinding disk. The parts *c* and *c'*, shown dotted, indicate the contour of the wheel *10* after trimming with the diamond and before engagement with the roller or tool *f* which is in fact a profile-finishing tool which 50 eliminates the necessity of forming the profile with diamond cutters. This is quite essential on grinding disks where the profile is extremely minute and is used for microscopic precision work.

The roller or tool *f* moves at right angles to the axis of the grinding disk, so that the pressures on the surfaces *c*, which surfaces are disposed on opposite sides of the grinding disk, will 5 receive equal pressure when the tool *f* is urged against the grinding disk 10 in proper alignment.

It will therefore be seen that in both the diamond trimming and profile-finishing operations of the complete dressing of the grinding wheel, 10 the pressures on opposing flanks of the grinding surfaces are substantially equal and opposite throughout all dressing operations.

What we claim as new, and desire to secure by Letters Patent of the United States is:

- 15 1. A device for dressing screw-threaded grinding disks, comprising two rigid carriers, each supporting two diamonds, the carriers being disposed so that the diamonds move in planes each parallel to the flank surfaces of the disk to be dressed, said diamonds being disposed in different planes, the diamonds for the flanks forming the point being in a higher plane than the other diamonds in that the point flanks are set inwardly in respect to the other flanks, means for moving said two carriers against both flanks at the same time, and means limiting the active movement of one diamond of each carrier by the other diamond of the same carrier, said means including a shoulder formed between the flanks.
- 20 2. In a device for dressing screw-threaded grinding disks, comprising two rigid carriers, each supporting two diamonds, the carriers being disposed so that the diamonds move in planes each parallel to the flank surfaces of the disc to be dressed, said diamonds being disposed in different planes, the diamonds for the flanks forming the point in a higher plane than the other diamonds in that the point flanks are set inwardly in respect to the other flanks, and means limiting the active movement of one diamond of each carrier by the other diamond of the same carrier, said means including a shoulder formed between the flanks, the improvement which consists in a means for moving said two carriers against both
- 25 30 35 40 45 flanks at the same time but in opposite direction to each other, and a profile roller for simultaneously further dressing the disk at its point for

convexly rounding the same, and at its shoulders for concavely rounding the same.

3. In a device for dressing screw-threaded grinding disks, comprising two rigid carriers, each supporting two diamonds, the carriers being disposed so that the diamonds may move in planes parallel to the proposed flank surfaces of the disk to be trimmed, said diamonds being disposed in different planes, the diamonds for the flanks forming the point in a higher plane than the other diamonds in that the point flanks are set inwardly in respect to the other flanks, and means limiting the active movement of one diamond of each carrier by the other diamond of the same carrier, said means including a shoulder formed between the flanks, means to permit said two carriers to impinge opposing flanks of the grinding disk simultaneously while both carriers are moving in the same general direction, and profile-finishing means movable at an angle of 20 90° from the axis of the revolving grinding disk to engage the same.

4. In a device for dressing screw-threaded grinding disks, comprising two rigid carriers, each supporting two diamonds, the carriers being disposed so that the diamonds may move in planes parallel to the proposed flank surfaces of the disk to be trimmed, said diamonds being disposed in different planes, the diamonds for the flanks forming the point in a higher plane than the other diamonds in that the point flanks are set inwardly in respect to the other flanks, and means limiting the active movement of one diamond of each carrier by the other diamond of the same carrier, said means including a shoulder formed between the flanks, means to permit said two carriers to impinge opposing flanks of the grinding disk simultaneously while both carriers are moving in the same general direction, and core-forming, profile-finishing means moving at 90° from the axis of the grinding disk to engage said disk shoulders formed between the flanks on each side of said disk to make said flanks concave in contour.
